UNITED STATES PATENT OFFICE.

MICHAEL CUDERA, OF SOLINGEN, GERMANY.

DOOR LOCK.

1,413,830.

Specification of Letters Patent. Patented Apr. 25, 1922.

Application filed December 28, 1918. Serial No. 268,760.

To all whom it may concern:

Be it known that I, MICHAEL CUDERA, a citizen of the German Republic, and resident of Solingen, Germany, have invented certain new and useful Improvements in Door Locks, of which the following is a specification.

This invention relates to an improved door lock having a sliding shaft and a trigger head pivoted thereon and normally locked but to 10 be disengaged electrically, and its novelty consists in the fact that the trigger head is prevented from turning by the abutment pin of a pivotal catch, which latter is turnable on a pivot of said shaft and which can be re- 15 tracted with its abutment pin to release said trigger head by means of an electromagnet and held in said position by means of a spring until, when opening the door and thereby turning the trigger head, said shaft is pressed 20 back and the catch, which is compelled to participate in said backward movement, is freed from said spring, whereupon it passes freely over the latter during the following return movement of the trigger head to its 25 initial position and again locks the latter therein by means of its abutment pin; the trigger head being provided with a shoulder which bears against the end of said shaft, said shoulder limiting the turning movement 30 of the trigger during the opening of the door and preventing its being carried beyond the path of said abutment pin.

The accompanying drawing shows the improved door lock: Fig. 1 is a front view of 35 the same with removed cover; Fig. 2 is a section on the line z—z of Fig. 1; Fig. 3 shows part of Fig. 2 in a plan view.

On the lock bottom a, a sliding shaft b is 40 movably held by a bolt d. A spring e, which is mounted on a pin f of the shaft b between the latter and the rear lock wall g, tends to press the shaft and trigger c toward the locking plate h. The trigger c is pivoted to a pin i of the shaft b so as to be turnable toward 45 the lock wall a, while it is pressed into its locking position by means of a spring k. Furthermore, on a pin l of the shaft b a pivotal catch m is mounted, straddling the end of the shaft b and having a pin n mounted 50 between its walls, said pin normally abutting the end of shaft b to hold catch m in proper position to allow the shoulder c¹ of trigger head c to contact with said pin n thus preventing trigger head c from turning in a direction to allow opening of the door. The

catch m is connected by a link o with a bolt p, over which engages a plate q, which is suspended so as to swing toward electromagnets r. Upon the latter being excited, the plate q is attracted and caused to strike against a head s of the bolt p, whereby the latter participates in its movement. The catch m is thereby swung about pivot l so that pin n is swung away from beneath the shoulder c¹ of trigger head c thus releasing said head to swing in a direction to allow opening of the door. As catch m is retracted, its forward edge passes the head of a spring t which snapping up in front of said catch holds it in trigger releasing position as shown in Fig. 3 in 70 dotted lines. Thereupon, the door can be opened, forcing the head of trigger c to turn over toward the lock wall a against the action of its spring k and issuing from the locking plate h but as far only as is necessary for 75 opening the door. Thereby, also the shaft b is pushed back sufficiently to free catch m from the spring t, while it is again adjusted to its original position by a spring z, the electromagnets being then no longer excited. 80 When closing the door, the head of trigger c is pressed backwards and, upon the door having been closed, again pressed into the locking plate h by means of the spring e, the abutment pin n coming then again in locking 85 engagement with the trigger head by action of spring z as above described. From outside, the door can be opened by means of a lock key in such a way that an arm u forming a pivotal knee-lever and engaging in a recess w of the shaft b is correspondingly adjusted by turning said key (see arrow, Fig. 1). This can also be effected from inside the door by means of a knob v, which is located 90 on the pin f outside the lock casing. The 95 electric disengagement of the trigger may be effected from any point or points where an electric contact for the electromagnets r can be provided.

What I claim, is:—

In a door lock, in combination, a sliding shaft having a trigger head pivoted thereon, a pivot on said shaft, a pivotal catch turnable on said pivot, an abutment pin on said catch located to normally prevent said trigger head 105 from turning, an electromagnet for retracting said pivotal catch with its abutment pin to release said trigger head, a spring to hold said pivotal catch in its retracted position, and a shoulder on said trigger head to bear 110

against the end of said shaft, said shoulder limiting the turning movement of the trigger during the opening of the door and preventing its being carried beyond the path of said 5 abutment pin, substantially as and for the purpose set forth.

In testimony whereof I have hereunto set

my hand in the presence of two subscribing witnesses.

MICHAEL CUDERA.
